UNITED STATES PATENT OFFICE

MORRIS J. HOFFMAN, OF CHICAGO, ILLINOIS

PRINTING MACHINE

Application filed November 21, 1930. Serial No. 497,107.

This invention relates to printing machines, and its principal object is to provide a machine for printing on a card or sheet a selected word or words, such as the name of a person, the date, and time of day. Another object is to provide a printing machine wherein are contained set type, plates, or other impression making elements, any selected one of which may be readily brought into printing position, in association with the printing elements of a time printing mechanism, whereby data, such as the name and identification number of an employee and the date and time of day, may be printed upon a time card, or the like, with one operation.

Another object is to provide a plurality of carriers for set type, plates, or the like, adjustably mounted in the machine for movement to and away from a printing position, whereby a great number of set type, plates, or the like, for printing names or other data may be contained in the machine of relatively small size. Another object is to provide, in a machine of the character set forth, means for printing other memoranda in connection with the name and time of day.

The invention consists in the several novel features of construction, arrangement and combination of parts hereinafter fully set forth and claimed.

The invention is clearly illustrated in the drawings accompanying this specification in which—

Figure 1 is a front elevation, partly broken out, of printing mechanism embodying a simple form of the present invention;

Fig. 2 is a detail fragmental plan illustrating certain ribbon rewinding mechanism;

Fig. 3 is a detail vertical cross section taken on the line 3 of Fig. 1, illustrating certain members of the ribbon winding mechanism;

Fig. 4 is a view, partly in plan and partly in horizontal section, of the machine with a certain cover plate removed, the line of section being indicated at 4—4 in Fig. 1;

Fig. 5 is a face view of a time card showing the information printed thereon with a machine embodying the present invention;

Fig. 6 is a vertical cross section of the machine taken on the line 6—6 of Fig. 1;

Fig. 7 is a detail fragmental front elevation, partly in vertical longitudinal section, of one of the type or plate carriers and type holders carried thereby;

Fig. 8 is a detail vertical cross section taken on the line 8—8 of Fig. 7;

Fig. 9 is a plan of a fragment of one of the type holders carried by the type carrier seen in Figs. 7 and 8;

Fig. 10 is a detail longitudinal section taken on the line 10—10 of Fig. 1; and

Fig. 11 is a plan of a portion of the machine illustrating the mechanism shown in Fig. 10.

Time cards are frequently issued to workmen for special work, and the workman's name and identification number, the time at which he starts work on the special job, the department from which he is assigned to the work, and the order number are usually printed upon the card, and, according to one phase of the invention, all of this data is printed in one printing operation on the time card. At the conclusion of the day's work on this job, the time card is again presented and the time printed thereon by the time printing mechanism of the machine.

The machine embodies a plurality of printing elements for printing words, figures, names of workmen, or the like, and the date and the time of day in association therewith, and, if desired, other data, such as a department number and the order number of the job, or the like. The machine further embodies means whereby any selected word printing element may be quickly brought into printing position adjacent the time printing means of the time printing mechanism, whereby a time card may be quickly and accurately made out. The details of construction of the machine for accomplishing this result will now be described.

Referring to said drawings, which illustrate one embodiment of the present invention, the reference character 14 designates the main frame of the machine which, as shown, comprises a front wall 15, a middle wall 16, a rear wall 17, and cross walls 18

and 19, all suitably connected together or formed as a single casting. Over the top of the several walls is a plate 20 which covers the mechanism contained in the compartments formed by said walls. A slot 21 is formed in the plate 20 at the printing position of the printing mechanism, and, as shown, said slot extends transversely across the machine.

For printing on a time card a selected word or words, letters or figures, as, for instance, the name and identification number of an employee, one or more carriers 22 are provided for the word printing elements; and in the present embodiment of the invention, two such carriers are illustrated. Conveniently, each carrier may be composed of spaced disks 23 and 24 mounted on a shaft 25 and adapted to support a multiplicity of circumferentially disposed type or plate holders 26. The type or plate holders 26 extend between the endmost disks 23 and are removably and replaceably secured thereon by pins 27 which extend through the type holders and through the type or plates and through apertures and notches formed in the end disks 23, as seen in Figs. 7, 8 and 9. The type holders and type or plates form the printing elements, referred to, that print a selected word or words, figures, and the like, such as an employee's name and identification number.

While the exact construction of the type holders is immaterial, the one shown has been chosen for the purpose of illustrating the invention. As shown, the type holders are of channel-like formation in which the type or plates are held, and when plates are employed, as seen at 28, it is preferred to employ a reinforcement bar 29 below the plate and to form end flanges on the plate and reinforcement bar which seat on the bottom of the channel and have perforations through which the pin 27 extends. The intermediate disks 24 are of less diameter than the end disks 23 and the type holders bear against the edges of said intermediate disks. The carriers 22 and type holders 26 may be of the character more fully shown and described in my prior Patent No. 1,489,530, dated April 8, 1924, for improvements in printing machines and type holders therefor.

The carriers 22 are rotatably mounted in a rectangular type carriage frame 30 mounted for movement lengthwise of the machine, whereby either of the two carriers 22 may be brought into printing position underneath the slot 21. As shown, the carriage frame 30 has grooved rollers 31 journaled thereon which run on tracks or rails 32 secured to the walls 15 and 16 of the main frame of the machine.

Each carrier shaft 25 extends forward through a slot 33 in the front wall 15 of the machine and has a hand or pointer 34 fastened upon its outer end which co-operates with a

dial 35 to aid the attendant in locating a printing element in printing position for printing a selected name. Each dial 35 is preferably in the form of a disk mounted upon a sleeve 36 which surrounds the forward end of the carrier shaft 34 and is provided with flanges 37 bolted or otherwise secured to the side of the carriage frame 30. From the above, it will be seen that the dials 35 are rigidly connected with the carriage frame 30 and move therewith.

In the peripheral portion of each dial 35 are open sided pockets 38 in which are held small cards 39 on which appear numbers corresponding with the identification numbers of the employees whose names are set in the type or contained on the plates for printing the names and identification numbers on the time cards. As a preference, the identification numbers of the employees are arranged in numerical order around the margin of the dials and the type or plates for printing the identification numbers of the employees are arranged in the carriers with the identification numbers in numerical order corresponding to the numbers on the cards on the dial, so that the attendant may, by turning the hand or pointer 34 to a selected number, bring the type or plate containing that identification number and name of the employee into printing position. A carrier may contain type or plates for printing as many as fifty or more names or employees, and the second type carrier is provided for holding type or plates for printing the identification number and names of other employees in case there are more employees than the one carrier can accommodate. As many carriers may be provided in the machine as are necessary in any special case.

As above stated, the carriage frame 30 is movable lengthwise of the machine, and a knob or handle 40 is provided on the outer end of one of the shafts 24, whereby the frame 30 and parts carried thereby may be shifted from one end of the machine towards the other end to thereby bring one or the other of the carriers into printing position under the slot 21. In order to hold the carriage frame and parts carried thereby in either of its two selected positions, spring actuated detents 41 are provided, one at each end of the main frame 14, which engage in depressions or sockets 42 formed in a side face of the carriage frame 30. In order to hold the carriers 22 in any of their selected positions, spring detents 43, one for each type carriage, are provided on the carriage frame 30 which engage with depressions or sockets 44 formed in the end disks 23 of the carriers.

Mounted on the main frame 14 between the walls 16 and 17 is time printing mechanism 45 having a series of printing wheels 46 for printing the date and time of the day. The time printing mechanism may take the form

of any of the well known types used in time stamps, time clocks, and workmen's time recording apparatus, and as the construction thereof is well understood, no detailed description is necessary so far as this specification is concerned. The type wheels 46 of the time printing mechanism are arranged to print in alignment with the type or plates carried by the type holders 26.

10 Between the time printing mechanism 45 and the carriers 22 are type wheels 47 which are rotatably carried in a supporting frame 48 and have type faces on their peripheral edges for printing numerals. The type wheels 47 may be employed for printing on the time card or other sheet the identification number of a department, or the like.

Between the time printing mechanism 45 and the wall 17 of the frame 14 is mounted a series of type wheels 49 which have type faces on their peripheral edges for printing the digits 0 to 9 and letters of the alphabet, this series of type wheels being arranged to print an identification number, such as an order number, or the like, on the time card. The type wheels 49 are rotatably mounted on a shaft 50 carried by the frame of the machine, and each type wheel 49 is provided on one side with a toothed wheel 51 which meshes with a rack bar 52 slidably mounted in grooved guide members 53 carried by the frame of the machine. The rack bars 52 are provided with upstanding fingers 54 on one end which project up through slots in the cover plate 20 and furnish means, whereby the rack bars may be adjusted back and forth to set the type wheels 49 to print any selected identification number.

20 In order to aid the attendant in setting the type wheels 49 to any selected identification number, indicating wheels 55, one for each type wheel 49, are provided on which are the digits 0 to 9 and letters of the alphabet corresponding with those on the type wheels 49, and said indicating wheels may be viewed through a slot 56 formed in the top plate 20. Each wheel 55 is provided with a toothed wheel 57, on one side thereof, which meshes with the rack bar 52 which operates the type wheel 49 associated therewith. The wheels 55 are rotatably mounted upon a shaft 58 carried by the frame of the machine. Spring detents 59 engage in sockets or depressions in the wheels 55 and hold them and therewith the rack bars 52 and type wheels 49 in any adjusted position.

25 For making an impression upon the time card, or other sheet, an ink ribbon 60 is provided which extends underneath the slot 21 and is carried by spools 61 and 62. The spools are mounted on shafts 63 and 64 carried by the frame of the machine, and mechanism is provided for rotating the spool 61 in a step by step manner to thereby advance the ink ribbon, and, as shown, said spool

actuating mechanism comprises a toothed wheel 65 on the shaft 63 and a pawl 66 connected by a link 68 to a spring operated lever 67 which is actuated in one direction by the impression making element of the machine. The shaft 64 of the other spool 62 may be rotated from a crank 69 by beveled gears 70 and 71 mounted on a shaft 64 and the shaft of the crank 69.

30 A rubber or other impression bar 72 cooperates with the ink ribbon 60 and type face of the printing mechanism to make the impression upon the time card or other sheet. The impression bar is carried by a stiff plate or bar 73 which is mounted on rods 74 connected at their upper ends by a knob 76 and guided in a guide member 75. Coiled compression springs 77 interposed between the knob 76 and upper ends of the guide member serve to retract the impression bar after it has been struck down after making an impression on the time card. The guide member for the impression bar is bolted or otherwise secured to the main frame of the machine and extends upward and overhangs the slot 21 of the top plate 20.

35 In Fig. 5 is shown a time card A containing data printed thereon by the machine illustrated. The data shown on the card is, of course, only illustrative of what may be printed by the machine.

40 In the operation of the machine, the attendant moves the carriage frame 30 to the proper position to bring the carrier 22, containing the set type or plate for a given employee's identification number and name, into the printing location and then turns the hand or pointer 34 to the number on the dial 35 corresponding to the identification number of the employee, which brings the set type or plate containing the employee's identification number and name into printing position directly under the slot 21. If an order number is used, the attendant manipulates the rack bars 52 to set the type wheels 49 so as to print the correct number of the order. If a department number is used, the type wheels 47 are adjusted to indicate the department in which the machine is used.

45 The time printing mechanism being entirely automatic, the type wheels thereof occupy the printing position for printing the correct time of the day. After having made the necessary adjustments, the attendant places the time card over the slot 21 and strikes down the knob 76, thereby bringing the compression bar down upon the card and making the imprint or impression thereon. In this manner all of the necessary information, namely, the identification number and name of the employee, the department, the date and time of day, and the order number, is printed upon the time card in one operation. At the conclusion of the work performed by the employee, the time card

may be stamped again to record the time of day, and this may be done by placing the card over the time printing mechanism only.

By the term "carrier" in the above specification and the appended claims is included any device in which a plurality of printing elements, such as plates, set type, and the like, are contained, and where said printing elements are interchangeable and any one is readily selectable and capable of movement into printing position in association with time printing mechanism.

More or less variation of the exact details of construction is possible without departing from the spirit of this invention. I desire, therefore, not to limit myself to the exact form of the construction shown and described, but intend, in the following claims to point out all of the invention disclosed herein.

I claim as new, and desire to secure by Letters Patent:

1. In a printing machine, the combination of a plurality of rotary carriers having lines of word printing elements circumferentially disposed thereon, a movable supporting frame in which said carriers are rotatably mounted, a dial and a pointer associated with each carrier for determining the printing position of any selected printing element thereof, each dial being rigidly connected with the frame and each pointer rigidly connected with a carrier, and printing mechanism having means for printing records in association with the word printed by said selected printing element.

2. In a printing machine, the combination of a case having a slot therein, a carriage frame guided for movement transversely of said slot, a plurality of carriers rotatably mounted on said carriage frame and adapted to be adjusted thereby into printing position underneath the slot, printing elements carried by said carriers and selectively movable underneath said slot, and time printing mechanism having means for printing a time record in association with data printed by said selected printing elements.

3. In a printing machine, the combination of a case having a slot therein, a carriage frame guided for movement transversely of said slot, a plurality of carriers rotatably mounted on said carriage frame and adapted to be adjusted thereby into printing position underneath the slot, printing elements carried by said carriers and selectively movable underneath said slot, time printing mechanism having means for printing a time record in association with data printed by said selected printing elements, dials, one for each carrier rigidly connected with said carriage frame, and a pointer connected with each carrier and co-operating with said dial to indicate the printing position of any selected printing element of the carrier.

4. In a printing machine, the combination of a plurality of carriers, each having a plurality of printing elements thereon and each carrier movable into printing position, means associated with each carrier for selectively bringing any printing element thereof into printing position, and time printing mechanism having means for simultaneously printing a time record in association with the word printed by a printing element of said carriers.

5. In a printing machine, the combination of a plurality of carriers, each having interchangeable printing elements mounted thereon, means for moving either carrier into printing position, means associated with each carrier for selectively bringing any printing element thereof into printing position, and time printing mechanism having means for simultaneously printing a time record in association with the word printed by said printing element.

6. In a printing machine, the combination of a case having a slot therein, a carriage frame guided for movement transversely of said slot, a plurality of carriers rotatably mounted on said carriage frame and adapted to be adjusted thereby into printing position underneath the slot, printing elements carried by said carriers and selectively movable underneath said slot, and indicating means associated with said carriers for indicating the printing position of selected printing elements.
